UNITED STATES PATENT OFFICE.

CLIFFORD H. McCASLIN, OF OAKLAND, CALIFORNIA.

PICTURE EXHIBITOR.

Application filed July 1, 1925. Serial No. 40,837.

To all whom it may concern:

Be it known that I, CLIFFORD H. McCASLIN, a citizen of the United States, and a resident of Oakland, in the county of Alameda and State of California, have invented a new and useful Improvement in Picture Exhibitors, of which the following is a specification.

This invention relates to improvements in exhibitors of the changeable type for pictures, printed matter and the like.

The general object of the invention is to provide for exhibiting so-called motion pictures in daylight and without the use of artificial light.

Another object of the invention is to eliminate the use of a shutter in the interval between displacement and substitution of pictures to be successively exhibited.

A further object is the provision of a relatively simple, cheap and durable device usable for amusement purposes in exhibiting animated records of events, and ideally adapted for use as an advertising device in store windows and the like.

The above and other objects are accomplished by instrumentalities pointed out in the following specification.

The invention is clearly defined in the claims.

A satisfactory embodiment of the invention is illustrated in the accompanying drawings forming part of the specification and in which

Figure 1 is a side elevation of the invention in use, parts therein being broken away to disclose the construction and relation of other parts.

Figure 2 is a fragmentary cross section taken on the line 2-2 of Figure 1, looking in the direction of the arrows.

Figure 3 is a vertical transverse section on the line 3-3 of Figure 7, looking in the direction of the arrows.

Figure 4 is a fragmentary section in plan approximately on the line 4-4 of Figure 1, except that the gear wheels are turned into a different position from that shown in Figure 1.

Figure 5 is a detail perspective of one of the movable pulley members.

Figure 6 is a perspective of the carrier detached and with the movable pulley removed.

Figure 7 is a central cross section of the device as viewed at right angles to Figure 3.

The device of the present invention comprises a casing *a* which is adapted to be arranged upright on a suitable support. A frame or observation opening 5 is centrally disposed in a wall 6 of the casing and permits an observer located in front of wall 6 to view matter exhibited through the opening and from the interior of the casing. The record sheet 7 is disposed within the casing and this record sheet is by preference made endless. For the purpose of this invention the record sheet may be of any desired length and may extend into the casing from a magazine 4 which provides a repository for the portion of the record not immediately within the casing *a*. In the embodiment shown the record sheet 7 is formed of photographic print paper upon which is imprinted photographically the pictures to be exhibited. The area of each picture forms substantially the area of the frame or observation opening 5 so that only a single picture may be observed through the opening 5 at any one time. A pair of oppositely disposed rolls 8 and 9 are arranged in the upper corner portions of casing *a* as viewed in Figure 7. These rolls extend transversely of the interior of casing *a* and are supported by hangers 10-10 as shown in Figure 3. The rolls provide a support for the intervening portion of the record which is located directly behind the wall 6 and opening 5. A second pair of oppositely disposed rolls 11 and 12 are located in the lower portion of casing *a*, as viewed in Figure 1, and the rolls 11 and 12 are parallel with each other and in vertical alinement with the rolls 8 and 9. For convenience I have shown the rolls 11 and 12 as having their ends journaled in one of the side walls 13 of casing *a* and in a partition 14 disposed within the casing and in spaced relation to the opposite side wall 15, as shown in Figure 3. The lower portion of the record is further supported by a pair of oppositely disposed intermittently operated feed rolls 16, 17 arranged parallel with one another and disposed in spaced relation and downwardly and inwardly from the rolls 11 and 12. The spindles 18 of feed rolls 16 and 17 are journaled in the wall 13 and partition 14. The section of the record between rolls 16 and 17 is supported by a take-up roll 19 corresponding in diameter to the rolls 16 and 17. The roll 19 is shown as being disposed below the axial planes of rolls 16 and 17.

and extends parallel with the said rolls 16 and 17, and its end portions are journaled in the wall 13 and partition 14 as shown in Figure 3.

In a device of the present type, it is to be understood that the use of the same will control the size of the picture to be exhibited. In the present embodiment pictures measuring 3" x 4" are employed and the record sheet 7 is so constructed that the long dimensions of the pictures will extend transversely of the sheet. In this way the sheet will be advanced across the opening 5 in the direction of the short dimensions of the pictures and opening 5 will be arranged to correspond with the disposition of the pictures. In view of the foregoing dimensions of the pictures, the diameters of the feed rolls 16 and 17 are such that in one revolution of either roll, the record is advanced for a distance corresponding to the short dimensions of two pictures or, in the present instance, approximately six inches. The pictures are, however, regardless of the distance through which the sheet moves in the rotation of either of the rolls 16 and 17 successively and periodically displayed through the opening 5. In order to accomplish this result, one section of the sheet is held against movement while the opposite section is advanced in the present instance for six inches. This movement on that section of the sheet between rolls 8 and 9 is intermittent and in a direction toward the right, as indicated by the arrows in Figure 7. The slack which results in the moving section of the record sheet is taken up by an apparatus operating with a see-saw motion and which is adapted to effect displacement and substitution in the opening 5 of pictures to be successively displayed. Referring now to Figures 6 and 7, an upper pair of correspondingly sized and axially parallel rolls 21 and 22 of a carriage provide a support for the section of record sheet 7 between the rolls 8 and 9. The rolls 21 and 22 are spaced apart, and the record sheet is directed downwardly between the said rolls so as to form a loop, as indicated by b in Figure 7. Rolls 21 and 22 are parallel with rolls 8 and 9, and are journaled in the opposite side members 23 and 24 of the carriage frame. The lower side members 25 and 26 of the carriage frame are connected to the upper members as by uprights 27 so that the carriage will move as a unit. The ends of the upper side members 23 and 24 are fixedly connected to one end of a plurality of flexible elements 28 which are supported by fixed pulleys 29-29 arranged in the corner portions of casing a and mounted on transversely disposed spindles 30-30. From pulleys 29 the flexible elements 28 extend vertically downward and are connected to cross-bars 31-31 at the opposite ends of

side bars 32 of a rock frame which has a centrally disposed shaft 33 journaled in centrally disposed bearings in the side plate 13 and partition 14, all of which is shown in Figures 3 and 7. Flexible elements 34 are connected to the ends of the lower side bars 25 and 26 and are supported by pulleys 35 disposed midway between the pulleys 29 and the axial plane of the rocking frame. From the pulleys 35 the flexible elements 34 extend vertically downward and are connected to the cross-bars 31 adjacent to the flexible elements 28. With this construction, the rocking frame operates to reciprocate the carriage across opening 5, the construction of the parts being such that the vertical central line of the frame located at a point between the rolls 21 and 22 moves beyond opposite sides of opening 5 in each reciprocation of the carriage. The portions of the record sheet between the rolls 17 and 19 and 16 and 18 are looped, as indicated by c and d and directed obliquely upwardly and outwardly, the adjacent sides of the loops being supported by oppositely disposed rolls 36 arranged parallel with and slightly below the axial planes of rolls 11 and 12, the said rolls 36 having their ends journaled in the side wall 13 and partition 14. The looped portions b, c, and d are connected to floatingly mounted supports by being extended around rolls 37, 38 and 39 which, as shown in Figure 5, are rotatably supported between outwardly extending arms 40 of brackets 41. Pulley sheaves 42 are mounted between centrally disposed spaced arms 43 extending outwardly from the base portions of bracket 41 and an endless flexible element 44 is trained around the sheaves 42 and directed upwardly between sheaves 45 centrally located on spindles 46 arranged in spaced relation and carried by the lower side bars 25 and 26 of the carriage. A pair of oppositely disposed fixed pulley sheaves 46 and 47 are supported by spindles 48 at points below the sheaves 45 of the carriage and the outer run of the endless flexible element 44 is directed laterally and in opposite directions from the sheaves 45 and trained around remote sides of the sheaves 46 and 47. The inner run of endless flexible element 44 is supported by fixed pulley sheaves 49 and 50 arranged downwardly and inwardly from the pulley sheaves 46 and 47 and carried by spindles 51 which are supported by the side plate 13 and partition wall 14.

With this construction it is obvious that when one of the feed rolls, for instance, the roll 16 is held stationary and the other feed roll 17 is rotated for one revolution, loop d will be shortened and loop b lengthened by reason of the movement of roll 38 toward roll 17 and the movement of roll 39 away from the upper rolls 21 of the carriage. It

will be noted, however, that by virtue of the movability of roll 39, the length of the descending movement of that roll will be equal to one-half the distance which the record 5 moved under the action of feed roll 17, it being assumed that the diameter of movable pulley sheave 42 is such as will afford this degree of movement, and a like amount of movement will be had on the part of the roll 10 38 which supports loop *d*. In this way the amount of record displaced will be taken away from loop *d* and will be taken into loop *b*. When loop *b* is so lengthened and loop *d* shortened and the carriage moved from the 15 position shown in Figure 7 to the opposite side of opening 5, then the area shown as being exposed in Figure 7 and indicated by *e* will be displaced and moved into the upper portion of the adjacent side of loop *b* 20 while the area uppermost on the opposite side of loop *b* will be substituted for *e* in the opening 5. During this action on the part of the carriage, it is assumed that the section of record between the rolls 8 and 9 is 25 stationary. When the carriage is on the remote side of the opening in Figure 7 as just stated and loop *b* extended, movement on the part of feed roll 16 in the direction of the arrows in Figure 7, will operate when 30 roll 17 is held stationary to shorten the loop to the extent shown in Figure 7 and thereby withdraw an amount of record equal to that previously taken into the loop. When this 35 has been done and the carriage moved to its original position, the second picture will be displaced from opening 5 and substituted by a third picture.

In Figure 1 a drive shaft 52 is journaled in side wall 15 and partition 14 with one end 40 extended beyond side wall 15 and adapted for connection to a suitable source of power which, in the present instance, is shown, as a manually operable crank handle 53. Drive shaft 52 in the embodiment shown, is rotatable clockwise and operates a spur gear wheel 54 keyed thereto to operate a pinion 55 with which it meshes and which is keyed to a shaft 56 upon which is disposed an idler gear wheel 57 which meshes with a correspondingly sized idler 58 fixedly secured to 45 spindle 18 by feed roll 19. Gear wheel 58 meshes with a gear wheel 59 of corresponding size keyed to a shaft 60. The gear wheels 57 and 59 rotate in a counter-clockwise direction, and through indirect connections intermittently operate feed rolls 16 and 17 respectively to rotate in a clockwise direction.

Referring now to Figure 1, toothed quadrants 61 and 62 are respectively rigidly secured to shafts 56 and 60, and their radii conform with the gear wheels 57 and 59. These quadrants are set with their middle lines approximately 180° apart and in rotating with the shafts 56 and 60 they abut a

pair of elongated teeth 63 and 64 of toothed pinions 65 and 66 which are rigidly secured to extensions of feed rolls 16 and 17 extending through the partition 14. The teeth of the pinions 65 and 66 mesh with the teeth of 70 the quadrants 61 and 62 when the pinions are turned by the action of the sides of the quadrants upon the fingers 63 and 64. A corresponding number of teeth are provided for the quadrants and pinions so that the 75 pinions are given one complete revolution by the quadrants in the rotation of the gear wheels 57 and 59. The elongated teeth are yieldingly engaged by detents in spring latch bars 67, as shown in Figures 1 and 2, 80 the latch bars being secured to the side wall 15 of the casing and sloped toward the fingers 63 and 64 so that the quadrants in rotating may pass over the inner faces of the latch bars to abut and disengage the teeth 85 63 and 64 therefrom. The idler 58 is provided with a crank pin 68 to which is connected one end of a connecting rod 69 that operates a cross head 70 slidable on guide bars 71 disposed on opposite sides of lock shaft 33 of the rocking frame and arranged upon the outer face of partition 14. A retractile spring 72 is connected at one end to a stud 73 carried by one of the side bars 32 of the rocking frame and extending through a curved slot 74 in the partition 14. The opposite end of spring 72 is secured to cross head pin 75. The spring 72 is tensioned by the movement of cross head 70 and operates to impart an abrupt rocking motion to the 90 100 rocking frame.

In the operation of the device, the continuous rotation of gear wheel 58 operates the cross head to move beyond a horizontal line 105 extending through the stud 73 and the center of the cross head. As the cross head recedes from this line, spring 72 is progressively tensioned until sufficient energy is had to rock the frame. In Figure 7 the parts are shown in the positions they occupy just prior to moving into the positions shown in Figure 1. That is to say, the connecting rod 69 is at the lower end of its stroke and the left hand edge of quadrant 62 is adjacent to finger 64. Quadrant 62 next turns pinion 66 which operates feed roll 17 to turn at a relatively high speed and complete one revolution by the time that quadrant 62 occupies the position shown in Figure 1. In this 110 action of the parts, it will be noted that latch 67 engages with tooth 63 so that feed roll 17 in turning displaces six inches of record from loop *d* and during this expenditure the record draws the floating support for loop *d* downwardly in Figure 7 and at the same time loop *b* is elongated by the descent of its floating support to the position shown by dotted lines in Figure 1. During this time 115 upward movement on the part of cross head 70 is storing energy in spring 72 which op-

erates to rock the frame at substantially the same time as the loops *b* and *d* of Figure 7 assume the positions shown in Figure 1. When the rocking frame responds to the action of spring 72 the movement will be decidedly abrupt and flexible elements 28 and 34 on the right of Figures 1 and 7 will shift the carriage to the right of opening 5 in Figures 1 and 7. At this time quadrant 61 moves into contact with finger 63 and imparts one revolution to feed roll 16 to withdraw the record from the section between the carriage and the said roll 16. The withdrawal of this section of the record shortens loop *b* and lengthens loop *c*, the length of loop *b* now being the same as shown in Figure 7 but disposed on the opposite side of opening 5. During the action last described on the part of the record, cross head 70 is moving downwardly and when quadrant 61 moves away from pinion 65, the energy of spring 72 operates to rock the frame and restore the carriage to the position shown in Figure 7. The surface area of loop *b* in the position shown in Figure 7 corresponds with the area of one picture so that in moving from the left to the right of opening 5, the picture contained in the loop *b* is substituted for the picture within opening 5, and the latter then becomes the picture within the loop when the parts are positioned as shown in Figure 7. When loop *b* is elongated as shown in Figure 1, it contains three pictures and of these the uppermost on the left of loop *b* is substituted for the picture previously displayed in the movement of the carriage to the right and the picture displayed becomes uppermost on the right side of the loop at the end of the movement of the carriage to the right. When loop *b* shortens, the first picture displayed and the succeeding picture are withdrawn and advanced to the right, and that which was previously the intervening picture is then exhibited through the opening 5. In this action of the parts, it will be noted that the pictures are not exhibited in the order of their arrangement on the sheet, but the sheet, nevertheless, advances with a step by step motion to the right, as indicated by the arrows in Figure 7. It will be further noted that the quick movement of the carriage and the peculiar displacement and substitution of the several pictures readily conveys the impression of continuity and apparent superimposition is effected without the employment of a shutter. It will, of course, be understood that in effecting apparent continuity in the pictures exhibited, their arrangement upon the record sheet will be such as will conform to the order in which they are displayed.

Although I have shown and described one embodiment of my invention, it is to be understood that the same is susceptible of various changes, and I reserve the right to

employ such as may come within the scope of the appended claims.

I claim:

1. A picture exhibitor comprising an observation frame, a record sheet forming a support for a plurality of successively disposed pictures, means for operating the record sheet to move with a step by step motion, and means adapted for displacing picture supporting sections of the sheet one by another in the opening of the frame in the interval between the movements of the record sheet. 75

2. A picture exhibitor comprising an observation frame, a record sheet forming a support for a plurality of successively disposed pictures, means for operating the record sheet to move with a step by step motion, and means supporting a section of the record sheet and movable in opposite directions across the opening of the frame and adapted for displacing picture supporting sections of the record sheet one by another in the opening of the frame in the interval between movements of the record sheet. 80

3. A picture exhibitor comprising an observation frame, a record sheet forming a support for a plurality of successively disposed pictures, means for operating the record sheet to move with a step by step motion, and means having a floatingly mounted member connected to the record sheet and movable across the opening of the frame for displacing picture carrying sections of the record sheet one by another in the opening of the frame in the interval between the movements of the record sheet. 95

4. A picture exhibitor comprising an observation frame, an intermittently movable record sheet having a plurality of picture supporting sections one of which is disposed across the frame and another extending as a loop and disposed adjacent to the frame, and means supporting the looped extension and movable across the frame to effect an interchange in the positions of said sections in the opening of the frame. 105

5. A picture exhibitor comprising an observation frame, an intermittently movable record sheet having a plurality of picture supporting sections one of which is disposed across the frame and another extending as a loop and disposed adjacent to the frame and means supporting the looped extension and movable across the frame to effect a simultaneous interchange in the positions of said sections. 115

6. A picture exhibitor comprising an observation frame, an intermittently movable record sheet having a plurality of picture supporting sections one of which is disposed across the frame and another extending as a loop and disposed adjacent to the frame and means supporting the looped extension and movable across the frame to effect a 125

simultaneous interchange in the positions of said sections in the interim between the movements of the record sheet.

7. A picture exhibitor comprising an observation frame, an intermittently movable record sheet having a plurality of picture supporting sections one of which is disposed across the frame and others extending as a loop and disposed adjacent to the frame, and means supporting the looped extension and movable across the frame to withdraw a picture therefrom into the loop and thereby transfer one of the pictures from the loop to the frame.
- 10 8. A picture exhibitor comprising an observation frame, an intermittently movable record sheet having a plurality of picture supporting sections one of which is disposed across the frame and others extending as a

loop and disposed adjacent to the frame, and means supporting the looped extension and movable in opposite directions across the frame to withdraw a picture therefrom into the loop and thereby transfer one of the pictures from the loop to the frame.

9. In a picture exhibitor, an observation frame, a continuous record sheet having spaced sections intermittently and successively operable to move in one direction, and oppositely disposed looped intervening sections one of which extends across the frame opening, and floatingly mounted supports for the looped sections operable simultaneously and intermittently to transfer a section of record from one of said looped sections to the loop section disposed across the frame.

CLIFFORD H. McCASLIN.
